UNITED STATES PATENT OFFICE.

HERBERT E. WHITE, OF YOUNGSTOWN, OHIO, ASSIGNOR TO THE GENERAL FIREPROOFING COMPANY, A CORPORATION OF OHIO.

REFRIGERATING-MACHINE.

1,245,544.

Specification of Letters Patent.

Patented Nov. 6, 1917.

Application filed August 3, 1915. Serial No. 43,379.

To all whom it may concern:

Be it known that I, HERBERT E. WHITE, a citizen of the United States, residing at Youngstown, in the county of Mahoning and State of Ohio, have invented certain new and useful Improvements in Refrigerating Machines, of which the following is a specification.

This invention relates to refrigerating machines of the intermittent absorption type, particularly designed for household and other uses where relatively small refrigerating capacity is required.

A primary object of the invention is to provide novel and practical means for positively and reliably changing the cycles of operation in the system regardless of pressure and temperature conditions. In that aspect, the present invention distinguishes from the type of refrigerating machines wherein the change of cycle is automatically brought about when the temperature in certain parts of the apparatus reaches a certain degree, or when the pressure in certain locations exceeds a predetermined amount.

In refrigerating machines, of the type wherein the change in the cycle of operations is automatically effected by the changes in temperature or pressure conditions, it has been found in practice that the instrumentalities required to bring about the necessary results are usually so delicate and unreliable as to frequently render the whole device inoperative, and thereby offset the advantages otherwise possessed by pressure and temperature controlled instruments.

Accordingly, a distinctive feature of the present invention resides in entirely dispensing with the use of temperature and pressure controlled instruments for effecting the change of cycle, and to substitute therefor a simple and economical cycle-changing device preferably including a simple type of water motor which may be conveniently operated by the cooling water for the system. Thus, the change of cycle may be brought about by a motor which can be set to operate at any speed, so that the time period of the generating and absorbing cycles is adjustable and determined by the speed of the motor regardless of pressure, temperature, or other conditions existing within or throughout the system. Also, the action of the refrigerating machine is thus made entirely automatic in

the sense that it continues its cycles so long as it is supplied with water and fuel.

With these and other objects in view which will be recognized by those familiar with the refrigerating art, the invention consists in the novel construction, combination, and arrangement of parts hereinafter more fully described, illustrated, and claimed.

The novel cycle-changing device and other features of the invention are necessarily susceptible of a wide range of structural modification without departing from the spirit or scope of the invention, as defined in the appended claims, but, for illustrative purposes, certain preferred and practical embodiments of the invention are shown in the accompanying drawings, in which—

Figure 1 is a side elevation of a refrigerating machine embodying the improvements contemplated by the present invention.

Fig. 2 is a similar view, but partly in section, of the opposite side of the machine.

Fig. 3 is a top plan view of the machine with a part of the piping omitted.

Fig. 4 is a rear end elevation of the complete machine.

Fig. 5 is a vertical cross sectional view on the line 5—5 of Fig. 2, illustrating the cross sectional form of the generator-absorber retort and of the condenser forming a part of the generating-absorbing unit.

Figs. 6 to 9 inclusive are similar diagrammatic sectional views of the form of water motor preferably employed as the prime mover for the automatic cycle-changing device.

Fig. 10 is a plan view of the motor cylinder case illustrating one form of construction for coupling together the paired circulating ports of the piston and valve chambers.

Fig. 11 is a cross sectional view on the line 11—11 of Fig. 10, illustrating the inlet and exhaust connections for the two chambers of the motor.

Fig. 12 is a detail sectional view on the line 12—12 of Fig. 11 illustrating the means for taking care of the exhaust from both chambers.

Fig. 13 of the drawings is a detail view of a preferable form of construction employed as the return valve for the piping connecting the generator-absorber with the condenser.

Similar reference characters designate cor-

responding parts throughout the several figures of the drawings.

A refrigerating system embodying the present invention includes in its general organization, a generating-absorbing unit and the novel cycle-changing device referred to. For purposes of illustration, the generating-absorbing unit is shown as principally comprising a generator-absorber proper, designated by the letter R, and a condenser designated by the letter C.

The generator-absorber R consists of a closed retort or tank of suitable capacity adapted to be partially filled with ammonia or an equivalent refrigerant liquor, and having associated therewith a heater 1 and a spray pipe 2 which are alternately operative as the retort R functions as a generator or as an absorber, as hereinafter fully explained.

The condenser C of the generating-absorbing unit primarily includes a set or sets of condenser coils 3, arranged within the water tank 4 receiving its supply of water at the top from a feeding pipe 5, and having a water overflow outlet 6 at a convenient point adjacent the top thereof. The piping 3, constituting the condenser coils, has separate circulating pipe terminals 7 and 8 respectively, the latter pipe terminal being in communication with the other parts of the apparatus to be presently explained, and the pipe terminal 7 being in communication with the circulating passageway 9 of a return valve 10. This return valve may be of any suitable construction, but is preferably of the simple form illustrated in Fig. 13. It consists of a casing 11 chambered to provide the passageway 9 and having a plurality of ports 12, 13 and 14, all in communication with said passageway and respectively communicating with the condenser pipe terminal 7, the refrigerant vapor pipe 15, and the refrigerant return pipe 16. The said return valve 10 also includes a ball or equivalent check valve 17 operating over a seat 18 in communication with the port 13, and limited or restrained in its movement by an adjustable stop screw 19 mounted in the valve casing 11 in line with the movement of the valve 17.

The refrigerant vapor pipe 15 extends from the point of connection with the return valve to the generator-absorber retort R and connects with the vapor outlet pipe member 20 arranged horizontally within the top portion of the retort. The refrigerant return pipe 16 extends from its point of connection with the return valve 10 to the retort and connects with the return pipe discharge member 21 arranged horizontally within the bottom portion of the retort, and provided with a plurality of discharging holes 22 opening into the interior thereof.

The heater 1 preferably consists of a Bun-

sen burner tube extending longitudinally of the retort beneath the same, and provided in its upper side with a series of burner openings 23, at which point the heating flame is provided for heating the retort during the generating cycle when the ammonia liquor is vaporizing to yield the ammonia vapor or gas. The gas fuel may be supplied to the Bunsen burner in any suitable manner, but preferably through a gas feed pipe 26 communicating with a suitable air mixer 27 at one end of the burner tube 1, and also in communication with the outlet port 28 of a gas control valve 29 whose inlet port 30 is in communication with the gas main 31 which supplies the fuel gas to the apparatus. This gas control valve 29 may be of any suitable construction including a turning plug 32 having ports arranged therein to provide for opening and closing the supply of gas to the pipe 26 according to the requirements of the apparatus, and this plug 32 has fitted to the spindle thereof a controlling pinion 33 which is operated periodically by the valve actuating member 34 of the cycle-changing device.

In connection with the gas supply for the heater or burner which supplies the heat for the retort R when operating as a generator, it is desirable to provide the line of piping 26 constituting the gas feed pipe 26 with a hand-controlled cut-off or regulating valve 35 which may be manipulated as occasion requires to increase or diminish the flow of gas through the pipe 26, or to entirely cut off the same. To maintain the apparatus in operative position at all times, there is associated with the burner tube 1 a pilot burner tube 36 having a connection with the gas supply main 31 so that a pilot light 105 may be maintained at all times over the burner tube to provide for automatically relighting the heater at the beginning of the generating cycle.

Also, the line of piping 26 preferably includes therein a thermostatic valve 37 of any suitable construction and which is in communication with a closed thermostat tube 38 screwed or soldered into one end of the retort and extending into the interior 115 of the latter. As indicated, the said thermostatic controlling valve 37 may be of any of the well known types, such as are used on domestic water tanks, and the same set to restrict the supply of fuel gas fed to the burner 1 as the temperature in the retort R rises. In this connection, it should be observed that it is desirable to limit the temperature of the generator-absorber during the heating or generating cycle to about 125° as a maximum, and it is for this purpose that the thermostatic valve is employed.

During the absorbing cycle of the machine, the cooling spray pipe 2 comes into play. This spray pipe is arranged longi-

tudinally of the retort above the latter and is provided at its under side with the longitudinal series of spray openings 25 (Fig. 5) through which the water issues, and is 5 jetted onto the top of the retort R. The cooling water will entirely envelop and flow over the external surface of the said retort, but will be prevented from flooding onto the burner tube 1 by reason of suitable baffles 10 39 provided upon the under side of the retort at both sides of the vertical plane of the burner tube 1. These baffles may be of any suitable form, but are shown as consisting of rounded projections offset from the 15 body of the retort and arranged so that the water will drip therefrom into a discharge pan 40 built within the bottom portion of the framework or stand F, and in turn discharging through the waste connection 41 to 20 the sewer.

The water supply for the spray pipe 2 is obtained from what may be termed the water main 42 for the apparatus, and the flow of water is primarily controlled automatically 25 by means of a three-way water control valve 43 having the inlet port 44 for the water main connection 42 and the separate outlet ports 45 and 46. The outlet port 45 is in communication with the water feed 30 pipe 47 which delivers water to the cooling spray pipe 2, and is provided with an independent hand controlled regulating valve 48, while the outlet port 46 connects with the water feeding pipe 5 for the condenser tank 35 4, said pipe 5 being also provided with its independent hand controlled regulating valve 49.

The three-way water control valve 43 includes a conventional form of turning plug 40 50 having ports coöperating with those of the casing, but according to the present invention the external stem of said turning plug is provided with a controlling pinion 51 engaged and operated by the oscillatory 45 valve actuating member 34 of the cycle-changing device. It will thus be seen that the said valve-actuating member of the said cycle-changing device engages and operates the controlling elements of both the gas and 50 water control valves 29 and 43 respectively, and alternately operates these valves at certain predetermined periods to provide for automatically changing the cycles of operation in the machine.

55 The cycle-changing device includes in combination with the valve controlling pinions 33 and 51 and the oscillatory valve actuating member 34, suitable motor controlled operating means for causing the slow 60 periodical oscillation of the said member 34. The motor controlled operating means for the actuator 34 include an intermittently propelled cam wheel 52 keyed upon a supporting shaft 53 journaled in suitable bearings 54 of the machine stand or frame.

This cam wheel 52 is provided therein with a cam-groove or slot 55 in which travels the bearing roller 56 carried by the crank arm 57 of the valve actuating member 34. The said groove or slot 55 is so formed that the travel of the roller 56 therein will cause the valve actuating member 34 to alternately swing in opposite directions, and also to dwell in a stationary position during each cycle of operation. It will also be observed 70 that the said oscillating valve actuating member 34 is a gear sector whose teeth mesh respectively with the controlling pinions 33 and 51, and which is pivotally mounted on a pivot axle or shaft 58 mounted in a stationary bracket or fixed part of the machine stand or frame, as clearly illustrated in Fig. 2 of the drawings.

To provide for intermittently propelling the cam wheel 52, the motor operated means 85 for the valve actuator also includes a pawl and ratchet mechanism comprising a ratchet wheel 59 fast on the supporting shaft 53, and a swinging pawl carrier 60 pivotally hung on the shaft 53 and carrying at its upper 90 end a pivotally mounted advancing pawl 61 engaging the teeth of the ratchet wheel or disk 59. (See Fig. 1). The pawl carrier 60 is preferably in the form of an arm projecting both above and below the supporting shaft 53, the lower extension 62 of said arm being arranged to play between a pair of oppositely arranged limiting stop screws 63 adjustably mounted in nut members 64 carried by the depending hanger bracket 65 100 mounted on the machine stand or frame. The adjustment of these oppositely disposed stop screws 63 in connection with the corresponding adjustment of the adjustable tap-pet screw 66 carried at the outer end of the piston stem 67 of the motor 68, provide a means for adjusting the throw of the pawl carrier 60, and thereby controlling the extent of movement of the cam wheel upon each active stroke of the operating motor. 105 On its outward movement, the piston stem 67 engages against the upper end portion of the pawl carrier 60, providing for the forward stroke of the advancing pawl 61, while the return or idle stroke thereof may be conveniently provided for by a retracting spring 69 whose opposite ends are respectively connected with the pawl carrier, as at 70, and to a fixed point of attachment, as at 71. Also, in order to check the ratchet disk 110 59 and the cam wheel 52 against backward movement of the idle stroke of the pawl carrier, a check pawl 72 is preferably employed. This check pawl is pivotally hung, as at 73, upon the lower end of the hanger bracket 65, and the engaging point or bill 73 of the said pawl is held in operative engagement with the teeth of the disk 59 by a counterbalance or weight 74 carried at one end 115 of the pawl arm.

The operating motor 68 for the cycle-changing device is preferably a simple form of slow speed water motor, and this type of motor may be most economically and advantageously employed in the machine, because it may be conveniently operated by the water which is necessarily supplied to the machine for cooling purposes. Accordingly, a motor supply pipe 75 may be conveniently 10 interposed between the inlets of the water motor 68 and the water main 42, the said pipe 75 being provided with a regulating valve 76 by means of which the speed of the motor may be easily regulated. The motor 15 is diagrammatically indicated in Figs. 1, 2, 3, 4 and 5 of the drawings.

As stated, the operating motor may be of any suitable single-stroke type, though the construction shown in detail in Figs. 6 to 20 12 inclusive in the drawings has been found to be practical for the purposes. The structural features of this type of motor are best shown in the diagrammatic views of Figs. 6 to 9 inclusive of the drawings. Referring 25 thereto, it will be seen that the motor consists essentially of a cylinder case 77 provided therein with the separate piston and valve chambers 78 and 79 respectively, each of which chambers has an inlet port connection 30 80 and 81. The piston chamber 78 has the inlet port connection 80 with the motor supply pipe 75, and the valve chamber 79 has the similar port connection 81 with the supply pipe 75, while the chamber 78 is provided 35 respectively upon opposite sides of the inlet port 80 with the exhaust ports 82 and 83, and the valve chamber 79 is provided with correspondingly located exhaust ports 84 and 85. The said several exhaust 40 ports may conveniently open into a common exhaust discharge passage 85^a having a pipe connection 85^b with the water tank 4 of the condenser C.

In addition to the inlet ports 80 and 81 45 and the exhaust ports 82, 83, 84 and 85, the two chambers 78 and 79 of the motor have other intercommunicating ports which provide for feeding and exhausting the water to and from the chambers in such a manner 50 as to cause the piston and the valve to slowly reciprocate to the various positions shown in the diagrammatic figures referred to. These ports are arranged to circulate the water from one part of one chamber to a 55 different part of the other chamber, and are arranged in pairs as clearly shown by the dotted lines in Figs. 6 to 9 of the drawings. The paired ports are respectively designated by the reference numerals 86—87, 88—89, 60 90—91, 92—93, and these various paired ports are connected by circulating passages 94 which may be conveniently placed in a suitable cored manifold 95 of the character illustrated in the elevational view of Fig. 10 65 of the drawings.

The piston chamber 78 accommodates a reciprocating piston member 96 rigidly connected with the inner end of the piston stem 67 which stem operates through a stuffing box 97 located at one end of the chamber 78. Structurally, the piston 96 is characterized 70 by a plurality of spaced piston elements or rings 98, and intermediate clearance necks 99 between said elements. The reciprocating valve 100, operating within the chamber 75 79, is of a similar construction to the piston itself, that is to say, consisting of a plurality of spaced piston elements 101, and intermediate connecting clearance necks 102, as plainly shown in the drawings. 80

Referring briefly to the operation of the slow speed water motor above described, it will be observed by reference to the diagrammatic views that Fig. 6 illustrates the relative positions of the piston and the valve 85 just after the piston stem 67 retreats from the pawl carrier 60. In this relative position of parts, water will pass in through the inlet port 80 into one of the spaces between the piston elements 98 and will be conducted 90 from the circulating port 88 to the circulating port 89, where it escapes behind one end of the valve 100 and causes the latter to be forced to the opposite end of the valve chamber 79, that is to the position shown in Fig. 95 7 of the drawings. While the valve 100 is moving to the position referred to, that is to the right (according to the positions shown in the drawings), the water within the right hand end of the chamber 79 will be forced 100 out of the port 93 to the port 92 and thence out through the exhaust passage 83, as will plainly appear by reference to Figs. 6 and 7 of the drawings.

Now, after the parts have assumed the 105 relative positions shown in Figs. 6 and 7 of the drawings, water will be admitted through the port 81, thence through the port 87 to the port 86, from which it passes behind one end of the piston 96, with the result 110 of driving the said piston forward (to the left in the drawings), and in this operation expelling water through ports 90 and 91 and out through the exhaust 85. This operation provides for bringing the parts in 115 the relative positions shown in Fig. 8 of the drawings. Referring to that figure of the drawings, it will be seen that water will be now admitted through the inlet port 80, thence to 92, and out of 93, with the result 120 of forcing the valve 100 to the left, at the same time expelling water through port 89 and port 88, and out through the exhaust port 82. This operation brings the parts again to the relative positions shown in Fig. 9 of the drawings, when water will again enter the inlet port 81, and passing through port 91 to port 90 will drive the piston 96 to the right and back to the position of parts shown in Fig. 6 of the drawings. From this 130

position the operation will be repeated indefinitely and automatically as long as the supply of water is delivered to the motor through the motor supply pipe.

Briefly summarizing the general operation of the refrigerating machine embodying the construction and arrangement described, it will be noted that the retort R of the generator absorber is partially filled with strong ammonia liquor. This liquor is generally of the temperature of the atmosphere in which the apparatus stands, and the piping and receivers connected with the generator absorber are free from air and filled with the ammonia gas. In starting the apparatus, the intermittently propelled cam wheel 52 is turned manually until the sector or valve actuating member 34 turns the controlling pinion 33 for the gas control valve 29 to such a position that the latter is opened and the fuel gas is fed from the gas main 31 to the gas feed pipe 26. Thence the gas is fed to the burner or heater 1 under the retort, where the gas is ignited from the pilot burner 36 fed directly from the gas main 31, as previously described. The burner or heater 1 thus becomes active, with the result of heating the generator absorber tank R and the ammonia liquor contained therein, thereby causing the liquor to yield up its vapor which passes out through the vapor pipes 20-15 through the return valve 10. During this cycle, that is while the retort is being heated from the burner, no ammonia gas or vapor will pass out of the retort through the pipes 21 and 16, because of the fact that the pipe 21 opens into the retort of the generator absorber below the surface of the liquor therein. Also, the pressure generated within the retort by the disengagement of the ammonia vapor will not force the liquor up the pipe 16, appreciably above the level thereof in the retort, because the pressure in the pipes 15 and 16 is substantially equalized. And, on account of the slight pressure in the pipe 15 necessary to unseat the ball or check valve 17, there will only be a slight but negligible rise of the liquor in the pipe 16, as will be readily understood.

The ammonia vapor or gas which is disengaged from the liquor in the retort passes through the return valve 10 and the pipe terminal 7 of the condenser coils into the latter, and at this point it will be understood that when the valve actuating member 34 of the cycle-changing device is in such a position that the gas control valve 29 is open to the passage of gas to the burner or heater, the three-way water control valve 43 is in such position that the water is free to pass therethrough into the water feeding pipe 5 which discharges the cooling water into the condenser water tank 4. This water flowing into the water tank 4 cools the con-

denser coils 3 and consequently the vapor or gas contained therein, and from the said coils 3 the cooled refrigerant vapor or gas passes through the circulating pipe terminal 8 to a suitable refrigerant liquid receiver 70 and expansion valve (not shown) and thence to the refrigerating coils in the usual manner.

In further reference to the action involved during the generating cycle, it will be noted that the operation described will continue until practically all of the ammonia is driven from the liquor in the retort, at which time the pressure in the cooling expansion coil (not shown) will be relatively 75 high. When the high pressure in the said cooling expansion coil reaches a predetermined degree, the motor parts will have assumed such positions as to cause the sector or valve actuator 34 to shift in a direction 80 that will turn off the gas control valve 29, and turn the three-way water control valve 43 to a position which cuts off water from the pipe 5 supplying the condenser tank, and turns on the water through the feed 85 pipe 47 leading to the cooling spray pipe 2. This operation cuts off the heat from the generator-absorber retort and initiates the cooling thereof, the effect of the cooling being to cause the now weakened liquor 90 within the retort to reabsorb the ammonia vapor or gas it has given off.

As soon as the ammonia vapor or gas commences to be absorbed in the water of the retort, the pressure in the entire system diminishes and the vapor or gas begins to naturally flow back to the generator absorber, but an interference to this flow occurs in the return valve 10. This interference is interposed by the ball or check valve 100 17 so that the ammonia vapor or gas is caused to pass through a circulating passage 9, into the return pipe 16, thence into the return pipe discharging member 21, and out through the discharging opening 22 passing 105 into the body of the liquid in the tank, facilitating solution. It will be understood, that the weak cold liquor in the tank has such a strong affinity for the ammonia vapor or gas, that the latter will be drawn back from the entire system until the pressure therein is very low, at or below one atmosphere. The motor is also timed or synchronized to that condition. That is to say, at this juncture in the absorbing cycle, the motor parts 110 will have assumed positions wherein the cam wheel is ready to swing the sector or valve actuator 34, so as to again turn on the gas to the burner for the retort, to turn off the water from the spray pipe, and to turn it 115 into the water feeding pipe for the condenser, thereby restarting the generating cycle. And, these cycles are automatically and alternately repeated while the machine 120 or apparatus is in operation.

From the foregoing, it is thought that the construction, operation, and many advantages of the herein-described improvements in refrigerating systems and machines will be readily understood without further description, but it may further be noted that changes in the form, proportion, and minor details of construction may be resorted to without departing from the spirit of the invention or scope of the appended claims.

I claim:

1. In a refrigerating machine, a generating-absorbing unit including a retort, a condenser, heating and cooling means for the retort, and a water feed pipe for the condenser, a gas-control valve for supplying fuel to the heating means, a water-control valve for supplying water to said cooling means, and to the condenser, an actuator segment common to both valves, a motor for operating said actuator segment to alternately open and close said valves at predetermined intervals.

2. In a refrigerating machine the combination with an extraneous source of power of a generating absorbing unit including heating and cooling means, a gas-control valve for supplying fuel to the heating means, a water-control valve for supplying water to the cooling means, a motor supported in an exposed position on a suitable part of the machine, and operated from said source of power, and a cycle-changing device actuated by said motor and including a valve actuator operatively connected with both valves and arranged to actuate the same alternately.

3. In a refrigerating machine, a generating-absorbing unit including heating and cooling means, control valves for both the heating and cooling means, and a motor operated cycle-changing device including an oscillatory valve actuator operatively connected with both valves, a rotatable cam wheel having a camming engagement with said actuator, and a motor for turning said wheel.

4. In a refrigerating machine, a generating-absorbing unit including heating and cooling means, control valves for both the heating and cooling means, and a motor operated cycle-changing device including an oscillatory valve actuator operatively connected with both valves, a rotatable cam wheel having a camming engagement with said actuator, and a water motor for turning said wheel.

5. In a refrigerating machine, a generating-absorbing unit including heating and cooling means, control valves for both the heating and cooling means, and a motor operated cycle-changing device including an oscillatory valve actuator operatively connected with both valves, a rotatable cam wheel having a camming engagement with

said actuator, and a water motor for turning said wheel and operated from the cooling water supply.

6. In a refrigerating machine, a generating-absorbing unit, including heating and cooling means, and control valves therefor having controlling pinions, and an automatic cycle-changing device including an oscillatory gear sector meshing with said pinions.

7. In a refrigerating machine, a generating-absorbing unit, including heating and cooling means, and control valves therefor having controlling pinions, and an automatic cycle-changing device including an oscillatory gear sector meshing with said pinions, and provided with a crank arm, and a motor propelled cam wheel having a groove engaging said crank arm.

8. In a refrigerating machine, a generating-absorbing unit including heating and cooling means and control valves therefor, and an automatic cycle-changing device comprising an oscillatory valve actuator operatively connected with said valves, a rotatable cam wheel having a camming engagement with said actuator, a pawl and ratchet mechanism for advancing said wheel, and a motor for operating the pawl and ratchet mechanism.

9. In a refrigerating machine, a generating-absorbing unit including heating and cooling means and control valves therefor, and an automatic cycle-changing device comprising an oscillatory valve actuator operatively connected with said valves, a rotatable cam wheel having a camming engagement with said actuator, a pawl and ratchet mechanism for advancing said wheel, and a reciprocating water motor for operating the pawl and ratchet mechanism.

10. In a refrigerating machine, a generating-absorbing unit including heating and cooling means and control valves therefor, and an automatic cycle-changing device comprising an oscillatory valve actuator operatively connected with said valves, a rotatable cam wheel having a camming engagement with said actuator, a pawl and ratchet mechanism for advancing said wheel, and a reciprocating slow-speed water motor for operating the pawl and ratchet mechanism.

11. In a refrigerating machine, a generating-absorbing unit including heating and cooling means and control valves therefor, and an automatic cycle-changing device comprising an oscillatory valve actuator operatively connected with said valves, a rotatable cam wheel having a camming engagement with said actuator, a pawl and ratchet mechanism for advancing said wheel, a slow-speed reciprocating water motor for operating the pawl and ratchet mechanism, and means for driving the motor from the cooling water supply.

12. In a refrigerating machine, a generating-absorbing unit including heating and cooling means, and control valves therefor having controlling pinions, and an automatic cycle-changing device including an oscillatory gear sector meshing with said pinions provided with an arm carrying a bearing roller, a rotatable cam wheel having a cam groove engaging said bearing roller, a pawl and ratchet mechanism for advancing the cam wheel, said mechanism having adjustable stroke-determining means, and a reciprocating motor for actuating said mechanism.
15. 13. In a refrigerating machine, a generating-absorbing unit including heating and cooling means, and control valves therefor having controlling pinions, and an automatic cycle-changing device including an oscillatory gear sector meshing with said pinions provided with an arm carrying a bearing roller, a rotatable cam wheel having a cam groove engaging said bearing roller, a pawl and ratchet mechanism for advancing the cam wheel, said mechanism

having adjustable stroke-determining means and an automatic check pawl, and a reciprocating motor for actuating said mechanism.

14. In a refrigerating machine, a generating-absorbing unit including heating and cooling means, and control valves therefor having pinions, and an automatic cycle-changing device comprising an oscillatory gear sector meshing with said pinions, a cam wheel operatively engaging the sector, a pawl and ratchet mechanism for advancing the cam wheel, said mechanism having a swinging pawl carrier, adjustable stroke-determining means, a retracting spring for the pawl carrier and an automatic check pawl, and a reciprocating water motor having a stem provided with an adjustable tap-pet screw engaging with the pawl carrier.

In testimony whereof I hereunto affix my signature in the presence of two witnesses. 45

HERBERT E. WHITE.
